MINIATURE ELECTRIC LAMP BULB AND
SOCKET COMBINATION

Paul Kollsman, New York, N. Y., assignor, by
mesne assignments, to Square D Company, De-
troit, Mich., a corporation of Michigan

Original application October 15, 1937, Serial No.
169,121. Divided and this application May 24,
1939, Serial No. 275,391

3 Claims. (CL. 176—32)

This application is a division of my co-pending
application Serial No. 169,121, filed October 15,
1937 which matured into Patent No. 2,171,431,
dated August 29, 1939.

5 This invention relates to electric illuminating
means, more particularly to a lamp, base and
socket combination which is particularly adapted
for use in an indicating instrument and which
permits an easy removal and replacement of the
10 lamp member from the front of the instrument.

In the illumination of indicating instruments,
particularly airplane instruments, it has been
found convenient to provide a cover glass or
15 sight glass for the instrument, with white paint
or diffusing means at the edge of the glass over
most of its periphery, and to provide adjacent
one point in the periphery, a very small miniature
lamp, which, by radiating into the exposed
20 edge of the glass, delivers light to the diffusing
means adjacent the edges of the glass cover plate,
from which it is thrown onto the scale graduations
and pointer.

Great difficulty has, however, been experienced
25 in obtaining a lamp and socket combination
which is sufficiently small to avoid interference
with the various instruments; which will stay
firmly in place in spite of the extreme vibration
encountered in airplanes; and which can be
30 readily changed when it burns out, with a
minimum of difficulty and a minimum of interference
with other instrument parts, and which can be
changed easily enough to permit the user to make
the change while in flight.

Thus, the problem requires that the lamp shall
35 be extremely small; that it shall be replaceable
from the front of the instrument; that it shall be held
firmly in place, and that it shall have members which are readily grasped by the operator's fingers to remove and replace the lamp.

40 The present invention provides a socket, a base
cooperating therewith and a miniature lamp held
therein, which is readily inserted and removed
from the front of the instrument into illuminating
45 relationship with the edge of the glass sight window
of the instrument.

Thus, an object of the invention is to provide
for the removable and replaceable mounting of
a miniature incandescent electric light bulb in
a socket, through the length of which the bulb
50 passes during the removal and replacement.

A further object of the invention is to pass a
miniature lamp bulb through the length of a
supporting socket and to anchor it therein while
making electric connection thereto.

55 A further object of the invention is to remove

and replace a lamp base by manipulation of a finger grip portion while passing the lamp bulb through a supporting socket.

Still a further object of the invention is to pass a lamp bulb through a socket into illuminating position and hold it therein by the interrelationship of contact pins and latch springs.

Still another object of the invention is to pass a lamp bulb through a socket, into illuminating 10 position with respect to an instrument dial, to hold the lamp in illuminating position by the application of a locking member, and to eject the lamp from the socket by a contact spring upon removal of the locking member.

Still a further object of the invention is to pass a lamp bulb through a socket, lock it therein, and make electric contact thereto through a ferrule adjacent one end of the lamp bulb, and a tip contact at the other end of the lamp 20 bulb.

Further aims, objects and advantages of this invention will appear from a consideration of the description which follows with accompanying drawing showing for purely illustrative purposes embodiments of this invention. It is to be understood, however, that the description is not to be taken in a limiting sense, the scope of this invention being defined in the appended claims.

30 Referring to the drawing:

Fig. 1 is a side view in section of an embodiment of this invention;

Fig. 2 is a side view in section of another embodiment of this invention.

35 In the embodiment shown in Fig. 1, the lamp having a glass bulb 10 enclosing a filament 11 is provided with a base consisting of a ferrule 12 and a center contact 13. The socket 14 may be made an integral part of an instrument casing 15 or it may be attached to the casing by suitable means as shown in the drawing.

The instrument casing shown in the drawing is provided with a window or cover glass 16 which may be used for distributing light received from the bulb through an aperture 17 in the socket and reflected onto indicating means enclosed in the casing by means of a suitable reflector 18 applied to the rim of the cover glass or otherwise. The socket provides a passage of 40 larger diameter than the diameter of the bulb into which the lamp is inserted.

45 The aperture of the socket may be closed by means of a cap member 19 secured to the opening of the socket member in a suitable manner,

a resilient rim 20 being shown for this purpose in the illustrated embodiment fitting in a snap button manner over the grooved end 21 of the sleeve of the socket.

5. A contact spring 22 is provided bearing against the ferrule 12 and connected to a suitable source of current. A center spring 23 is associated with the center contact 13 and connected to the other terminal of the source of electrical energy.

10. The lamp is inserted, base first, into the socket, thereby compressing the center spring 23. The cap member 19, having a finger operable grip portion 24, is then secured to the socket and bears with an extended configuration 25 against 15 the bulb, thus holding the lamp in place.

If it is desired to exchange the bulb, the cap member is simply pulled off, whereupon the spring 23 ejects the lamp from the socket either entirely or far enough to be grasped and removed 20 by hand, whereupon another lamp may be inserted in the hereinbefore described manner.

Another embodiment of this invention is shown in Fig. 2 in which corresponding parts are designated by corresponding reference numerals.

25. In this embodiment, the cap member 19 is of smaller dimensions and provided with a snap ring 20' fitting into a groove in the socket. A sleeve 25 movable against the action of a compression spring 23' in a bore 26 of the socket is 30 provided for connecting the center contact of the lamp in the electrical circuit.

Obviously, the present invention is not restricted to the particular embodiments shown and described. Other forms may be designed without 35 departing from the spirit of the invention.

What is claimed is:

1. The combination of a lamp socket member 40 providing a tubular passage and having an opening at one end and an aperture at one side for the emission of light; a lamp comprising a filament, a bulb of smaller diameter than said passage, and a tubular base, said lamp being insertable into said passage through said opening into a position in which the filament is adjacent to 45 said aperture; a spring at the bottom of said passage adapted to be distorted by insertion of said

lamp; and a cap member having a finger operable grip portion and means for removably fastening it to the socket member at the said opening of said passage, said cap member having a configuration bearing against said lamp thereby compressing said spring. 5

2. The combination of a lamp socket member providing a tubular passage and having an opening at one end and an aperture at one side for the emission of light; a lamp comprising a filament, a bulb of smaller diameter than said opening and passage, and a base, said base comprising a ferrule and a center contact, the lamp being insertable through said opening into said passage into a position in which the filament is adjacent 10 to said aperture; a spring at the bottom of said passage adapted to be distorted by insertion of said lamp and forming one socket contact associated with said center contact; a second resilient contact in said passage associated with said ferrule; and a cap member having a finger operable grip portion and means for removably fastening it to said socket member at the said opening of said passage, said cap member having a configuration bearing against said bulb thereby compressing said spring. 15

3. The combination of a lamp socket member providing a tubular passage and having an aperture at one side for the emission of light; a lamp comprising a filament, a bulb of smaller diameter than said passage, and a base, said base comprising a ferrule and a center contact, the lamp being insertable into said passage into a position in which the filament is adjacent to said aperture; a spring at the bottom of said passage adapted to 20 be distorted by insertion of said lamp and forming one socket contact associated with said center contact; a second resilient contact in said passage associated with said ferrule; and a cap member having a finger operable grip portion and snap means for removably fastening it to said socket member at the opening of said passage, said cap member having a configuration bearing against said bulb thereby compressing 25 said spring. 30
